UNITED STATES PATENT OFFICE.

ISAIAH S. EMERY, OF ROCHESTER, NEW YORK.

POCKET-BOOK.

SPECIFICATION forming part of Letters Patent No. 316,346, dated April 21, 1885.

Application filed November 29, 1884. (No model.)

To all whom it may concern:

Be it known that I, ISAIAH S. EMERY, a citizen of the United States, residing at Rochester, in the county of Monroe and State of New York, have invented certain new and useful Improvements in Pocket-Books, of which the following is a specification, reference being had therein to the accompanying drawings.

10 Figure 1 is a perspective view of my pocket-book closed. Fig. 2 is a perspective view of my pocket-book, exposing the frame or sheath and its closing flaps. Fig. 3 is a view of a modification of the device of Figs. 1 and 2, 15 showing the case more simplified, the flap inclosing and holding in place the cards. Fig. 4 is a transverse section illustrating the flexible frame applied to the cover. Fig. 5 is a 20 similar view showing the frame made like a bellows.

This invention relates to pocket-books wherein cards of any description can be protected from abrasure; and it consists in a 25 foldable covering having suitably secured to it a case adapted to receive and to expose to view the cards.

The object is to provide a case or envelope which will not only preserve the card, but will keep entire and intact the printing or 30 writing on said card.

It is well known among railroad-men that the pass commutation tickets or cards which passengers carry are oftentimes rendered useless or doubtful from general use in the pocket 35 without a suitable covering. Now, my object is to provide a special pocket-book which, among various other uses, is very well adapted to contain railroad-passes or time-tickets, and which consists of an envelope, A, having 40 two flaps, a and a' , and an intermediate portion, a^2 . To the intermediate portion, a^2 , of the flexible envelope I secure or attach, by means of cementation, stitching, or otherwise, a frame, B. This frame exposes a space sufficient to identify at once a note or card, and it is especially designed for holding 45 safely a card or other matter. The frame B is secured to the part a^2 , as aforesaid, by its flanges b , and thus forms in my pocket-book 50 a recess, b' , open in front or face, having one side open, as at b' . It is constructed with three edges closed and one edge, b^3 , open. In Fig. 5 I show the edges of the frame made like a bellows—to wit, they are collapsible—for the

purpose of accommodating themselves if more 55 than one pass or card or other device should be placed in the recess.

It will be observed that I show an envelope pocket-book having an open frame for exposing to view the matter which it contains; 60 also, that either edge may be open or slotted, so that the pass or other device can be removed from the frame.

It may be desirable that the open edge of the frame should be provided with a folding 65 shield, especially if the opening is at the end of the pocket-book. I therefore provide a supplemental flap, C, which will interfold with the flaps a and a' of the pocket-case and safely retain the matter inclosed therein.

70 From the foregoing description it will be seen that I employ in a pocket-book an open frame made entire and united to the lining and backing, and I also leave one edge or end open, for the purpose of readily introducing 75 into and removing from the same the pass, card, or other device. I furthermore provide a flexible flap or shield, which will prevent the matter from being lost.

Having described my invention, I claim— 80

1. A pocket-book having two flaps and an intermediate portion, as described, in combination with a frame attached or secured to said intermediate portion and open at one end, substantially as described.

85 2. A pocket-book composed of a central portion and two lapping portions, in combination with a collapsible open-faced frame having one end open, for the purpose described.

90 3. A pocket-book having two flaps and a central portion, in combination with a central open-faced frame secured thereto having one edge open, for the purpose described, and a flap adapted to close said opening, as specified.

95 4. As an improved article of manufacture, a pocket-book having a back made with three flaps, in combination with an open-faced frame having a slot or opening at one edge arranged 100 to be closed by one of said flaps, all of the said flaps being adapted to be folded, as described.

In testimony whereof I affix my signature in presence of two witnesses.

Witnesses: ISAIAH S. EMERY.
